UNITED STATES PATENT OFFICE.

WILLIAM E. ELLIOTT, OF LYNN, MASSACHUSETTS, ASSIGNOR TO AMERICAN BUTTON & FASTENER CO., OF AUGUSTA, MAINE, A CORPORATION OF MAINE.

FASTENER-ATTACHING MACHINE.

Application filed November 11, 1920. Serial No. 423,312.

To all whom it may concern:

Be it known that I, WILLIAM E. ELLIOTT, a citizen of the United States, residing at Lynn, in the county of Essex and State of Massachusetts, have invented certain Improvements in Fastener-Attaching Machines, of which the following description, in connection with the accompanying drawings, is a specification, like reference characters on the drawings indicating like parts in the several figures.

My invention relates to machines for attaching fasteners by means of securing devices, with which are associated cooperating devices designed, for example, to protect from tearing the material upon which the fasteners are mounted. In the Patent No. 1,220,829, granted to me on March 27, 1917, is disclosed work of this character, the fasteners being attached to fabric by means of staples having their legs upset over washers, said washers distributing over considerable areas of the fabric the tearing stresses of the clinched staples. An object of this invention is to provide an efficient machine for effecting such attachments, though not, it is to be understood, necessarily limited to operation upon the particular form of protective device illustrated in the previously mentioned patent.

In the attainment of this object, a feature of my improved machine involves the combination with means, acting in the initial operation of said machine, for delivering to attaching mechanism fasteners and their securing devices, as buttons and staples, of means for delivering cooperating devices, or washers. This delivering or feeding means is preferably arranged to grasp and hold each protective device in proximity to the attaching mechanism in alinement with a delivered securing device, so they may be assembled and the latter set in place. I have illustrated the protective devices as formed in a series, as in the above-mentioned patent, and the delivering or feeding mean is shown as adapted to engage simultaneously a plurality of the series. By this expedient, one protective device is advanced to the attaching position, and the succeeding device moved forward in preparation for such advance upon the next operation of the machine. More specifi-

cally, there is disclosed, co-operating with a button and staple-delivering and staple-setting means, the latter including an anvil, a washer-presenting mechanism in the form of feeding jaws movable into and out of co-operation with the anvil.

A further feature of the invention concerns the severing of the protecting devices, when they are arranged in a strip, from the connected devices. This separation of a protective device for attachment occurs, in the present embodiment of the invention, while said device is held against displacement by the delivery means, which may also similarly hold the remainder of the strip ready for the succeeding delivery. I have also shown, independent of the delivering means, means for holding the devices during the attaching operation by a retaining member acting upon them. This retaining means, when employed in connection with a series, is movable between its devices; and with such devices joined to one another, as described in the Patent No. 1,220,829, this engagement serves to support the entire series. In the illustrated embodiment of the invention, the retention of the strip is effected by a severing means. That is, with a strip of washers connected by reduced portions, a cutter acts upon said reduced portions, while a projection from the cutter extends between the washers to exert the retaining effect.

A particular embodiment of the invention is illustrated in the accompanying drawings, in which—

Fig. 1 represents my improved attaching machine in top plan with the raceway and driving mechanism removed;

Fig. 2 is a side elevation of the machine;

Fig. 3, a similar view taken from the opposite side;

Fig. 4, a detail in top plan of the anvil and more closely associated elements;

Fig. 5, a vertical section on the line 5—5 of Fig. 4;

Figs. 6 and 7, top plan views of the portions of the machine illustrated in Fig. 4, showing the parts occupying successive positions;

Fig. 8, a vertical section on the line 8—8 of Fig. 7;

Fig. 9, a view, similar to Fig. 8, illustrat-

ing the succeeding step and including the driving mechanism;

5 Figs. 10 and 11, top plan views, giving steps of the feeding and severing operations succeeding that of Fig. 9;

Fig. 12, a perspective view of the cutting and retaining member;

Fig. 13, a like view of the feeding mechanism inverted;

10 Fig. 14, a vertical section through work including a button attached by the present machine; and

15 Fig. 15, a view in perspective of a strip of washers adapted for employment in the machine.

Generally, the machine may be of the type represented in the application filed in my name May 9, 1919, Ser. No. 295,825. The arrangement of the frame 10, with its upstanding portion 12 carrying the anvil 14, and the co-operating yieldable work-clamping raceway 16 for buttons carrying assembled staples, may be the same, as may also the oscillatory driving and feeding member 18. 20 Of these parts it is only necessary to say that an eccentric 20, rotated by a main driving shaft 22 journaled transversely of the frame, is connected through an eccentric rod 24, lever 26 and connecting rod 28 to levers 30 and 32. These levers, in their oscillation produced by the rotation of the eccentric, move the raceway into and out of contact with the work upon the anvil, the pressure against the work being yieldable 35 by virtue of the inclusion of a spring 34 in the connections. They also cause projections upon the driver 18 to set in the work staples S, which are threaded through the eyes of buttons B, carried in a series in the raceway, there being with this setting action by the forward projection 36, a simultaneous feeding by the projection 38 of the succeeding staple and button in the series in preparation for the next setting operation. 40

45 In some materials, as the fabrics of which gaiters are made, the area presented by the clinched ends of the staple legs offers too little resistance to prevent their pulling through, and to overcome this, the button attachment with its protective washer strip of Patent No. 1,220,829 was devised. To deliver these or other washers to the attaching mechanism, feeding mechanism is 50 mounted to move upon an inclined surface 40 of the frame portion 12 adjacent to the anvil 14. This feeding mechanism includes a carrier slide 42 arranged for reciprocation upon the surface 40, the under side of which 55 slide is recessed to receive oscillatory washer-holding jaws 44, 44, pivoted upon the slide at 46, 46. At the extremity of the jaws is a pair of opposed recesses 48, 48, and just to the rear of these are similar recesses 50, 50, these two pairs being so lo-

cated as to grasp simultaneously adjacent washers W, W. Extending laterally from opposite sides of the slide 42, near the rear, are projections 52, 52 engaged by arms 54, 54 fixed upon a shaft 56 arranged to turn in the frame portion 12. The shaft also has secured upon it an arm 58, joined by a connecting rod 60 to one arm of a bell-crank lever 62 fulcrumed upon a standard 64 rising from the frame 10 near its center. Another arm of the lever 62 bears an anti-friction roll co-operating with the periphery of a cam 66 fast upon the shaft 22. Suitable springs urge this and similar operating levers of the machine toward their cams. 70 Formed opposite each other upon the rear extremities of the jaws 44 are rounded projections 68, lying within a recess 70 upon the upper side of an actuating slide 72 mounted to move between the surface 40 of the frame and the top wall of the recess in the carrier slide 42. Depending from the under portion of the slide 72 is a projecting member 74, engaged by an arm 76 upon a shaft 78 journaled in the frame. The shaft has fixed to it another arm 80, to which is articulated a connecting rod 82, also pivoted to a bell-crank lever 84, fulcrumed upon the standard 64. The lever 84 carries a roll co-operating with a cam 86 turning with the shaft 22. The cams 66 and 86 may leave the carrier slide 42 and the actuating slide 72 stationary, as when the levers which control the slides are out of contact with the cam peripheries, as is 90 shown in connection with the lever 62, or when the cam surfaces are concentric to the axis of rotation, or may produce a movement of the slides when either or both of the cams departs from this concentric relation, in the latter case the action being differential. The effect of the cams upon the slide 42 is to produce a reciprocation of the feeding jaws toward and from the anvil, and upon the slide 72, either when this is 100 moved alone, or differentially with respect to the slide 42, is to oscillate the jaws to cause them to grasp or release the washers W. These washers are introduced to the machine in strip form through an opening 88 in the frame portion 12, passing therefrom between the jaws across a surface 90 at the top of this portion. The action of the jaws will be more fully developed in connection with the statement of operation. 110

115 Just at the rear of the anvil, movable through a bore 92 in the frame portion 12, intersecting the washer-supporting surface 90, is a reciprocatory member 94, preferably adapted to both sever a contracted portion 120 w joining adjacent washers W to form the strip, thus freeing a washer which has been utilized, and to retain the washers against displacement, as when the feeding fingers are being shifted to grasp succeeding wash- 130

ers. For the first-mentioned purpose, the member 94 has at its upper end a cutting edge 96 co-operating with a die opening 98 in a plate 100 extending across and being spaced from the frame surface 90. This plate 100 also furnishes with the frame surface a guide-way holding the washer strip in the proper relation to the anvil. At each side of the cutting edge, to straddle the reduced portions *w* of the washer strip, are projections 102, 102. These, when raised between the washers before the cutting edge contacts with a portion *w*, engage the upper washer of the strip to hold the entire series against movement downward through the opening 88. To impart reciprocation to the member 94, it is pivoted upon an arm 104, fast upon a shaft 106, which also has secured to it an arm 108. A connecting rod 110 joins this arm 108 to a lever 112 fulcrumed upon the standard 64. An anti-friction roll carried by an arm of this lever rests upon the periphery of a cam 114 fast upon the shaft 22. The contour of the cam is such as to first raise the member 94 with the projections 102 between the washers, at which time there is a period of rest to permit the exercise of the retaining function. Thereafter the rise of the member continues, and the cutting edge co-operating with the die opening severs the connecting portion of the strip. The member is then lowered to its initial position.

In considering the operation of the machine, it will be assumed that it has acted, and as a result of this a severed washer is held in the recesses 48, 48 of the feeding jaws, while the succeeding washer of the strip, connected to its companions by the reduced portions, is held by the recesses 50, 50, the jaws at this time being at their extreme rearward position. At the beginning of the succeeding cycle, the eccentric 20 causes the gradual descent of the raceway 16 and driver 18. During this movement, the jaws are advanced by the cam 66 from the position shown in Fig. 6 until openings *o*, *o* of the severed washer are over clinching depressions 116 of the anvil in a position to receive the points of the leading staple *S* in the raceway. The parts are now as illustrated in Fig. 7 of the drawings. The member 94 at this time reaches the point appearing in Fig. 8, and there rests temporarily with the projections 102 between the first undetached washer and the one below it in the strip. Immediately following this, the lowest staple carried down the raceway by the driver projection 36 is passed through the openings *o* of the upper previously-severed washer, and under the pressure of the driver is forced through the fabric and clinched beneath the washer. This produces the attachment of the button *B*, best shown in Fig. 14. After the forward

washer has been engaged by its staple, so that it is held against displacement, and with the remaining portion of the strip retained by the projections 102, the jaws 44 are separated by a differential movement of the carrier 70 slide 42 and actuating slide 72, as appears in Fig. 10, and are carried downwardly to their initial position by the travel of the carrier slide. When the jaws have reached this position, they close upon the two succeeding washers of the strip, and the member 94 completes its upward stroke, severing the forward washer by means of the cutting edge 96. At this time the works has been released by the retreat of the driver and raceway, so that it may be shifted to the position at which another button is to be attached. The machine is now in condition for the succeeding operation.

Having described my invention, what I claim as new and desire to secure by Letters Patent of the United States is:

1. In a fastener-attaching machine, attaching mechanism, means for delivering to the attaching mechanism fasteners and their securing staples, and means acting in the initial operation of the machine for delivering to the attaching mechanism a device for cooperation with a staple.
2. In a fastener-attaching machine, attaching mechanism, means for delivering fasteners and securing devices therefor to the attaching mechanism, and means for delivering to the attaching mechanism a device for cooperation with a securing device, said delivering means being arranged to grasp the co-operating device in proximity to the attaching mechanism and there hold said co-operating device for engagement by the securing device.
3. In a fastener-attaching machine, attaching mechanism, means for delivering fasteners and securing devices therefor to the attaching mechanism, and means for feeding a series of devices for co-operation with the securing devices, said feeding means being arranged to engage simultaneously a plurality of the co-operating devices.
4. In a fastener-attaching machine, attaching mechanism, means for delivering fasteners and securing devices assembled therewith to the attaching mechanism, and means for grasping a protective device and advancing it to the attaching mechanism for association with the fasteners and securing devices.
5. In a fastener-attaching machine, attaching mechanism, means for delivering fasteners and securing devices therefor to the attaching mechanism, and means for feeding a protective device transversely to the direction of delivery of the fasteners and securing devices, said feeding means being arranged to engage a protective device

- at opposite sides of the attaching mechanism and hold said protective device in alinement with a delivered securing device.
6. In a fastener-attaching machine, attaching mechanism, means for delivering fasteners and securing devices therefor to the attaching mechanism, and means for feeding a protective device transversely to the direction of delivery of the fasteners and securing devices, said feeding means being arranged to hold a protective device in alinement with a delivered securing device and to release said protective device after its engagement by the securing device.
- 10 7. In a button-attaching machine, means for delivering buttons and associated staples, staple-setting means co-operating with the delivering means, and washer-presenting mechanism co-operating with the delivering and setting means.
- 15 8. In a button-attaching machine, means for delivering buttons and associated staples, staple-setting means cooperating with the delivering means, and mechanism arranged to grasp a plurality of washers and advance them successively toward the setting means.
- 20 9. In a machine for attaching buttons by means of staples, an anvil, a staple driver co-operating therewith, means for supplying to the anvil and driver buttons with staples threaded through their eyes, and means for delivering washers between the anvil and driver.
- 25 10. In a machine for attaching buttons by means of staples, an anvil, a staple driver co-operating therewith, means for delivering a staple with a button between the anvil and driver, and feeding jaws arranged to grasp between them an object which is to receive the staple and movable into and out of co-operation with the anvil.
- 30 11. In a machine for attaching buttons by means of staples, an anvil, a staple driver co-operating therewith, means for delivering a staple with a button between the anvil and driver, feeding jaws, a carrier therefor, means for moving the carrier toward and from the anvil, and means for opening and closing the jaws.
- 35 12. In a machine for attaching buttons by means of staples, an anvil, a staple driver co-operating therewith, feeding jaws co-operating with the anvil, a carrier for the jaws, and differentially movable means for reciprocating and oscillating the jaws.
- 40 13. In a machine for attaching buttons by means of staples, a frame, a guide-way formed therein to receive a strip of washers provided with openings for the staple-legs, an anvil adjacent to the guide-way, a driver co-operating with the anvil, means for delivering staples to the anvil and driver, and means for advancing the strip of washers through the guide-way to the anvil with
- their openings in alinement with the staple-legs.
- 45 14. In a machine for setting buttons by means of staples, a frame having a guide-way to receive a strip of washers, an anvil adjacent to the guide-way, a driver co-operating with the anvil, and feeding jaws arranged to grasp the washers at opposite edges and movable in the guide-way.
- 50 15. In a machine for attaching buttons by means of staples, a frame having a guide-way to receive a strip of washers, an anvil adjacent to the guide-way, a driver co-operating with the anvil, and feeding jaws for the washers co-operating with the anvil through the guide-way, said jaws having adjacent recesses to engage succeeding washers of the strip.
- 55 16. In a fastener-attaching machine, attaching mechanism, means for delivering fasteners and securing devices therefor to the attaching mechanism, means for delivering to the attaching mechanism a device for co-operation with a securing device, and movable retaining means acting upon a co-operating device to hold it against movement in the direction of delivery.
- 60 17. In a fastener-attaching machine, attaching mechanism, means for delivering fasteners and securing devices therefor to the attaching mechanism, means for feeding a series of devices for co-operation with the securing devices, and retaining means movable between adjacent devices of the series.
- 65 18. In a fastener-attaching machine, attaching mechanism, means for delivering fasteners and securing devices therefor to the attaching mechanism, means for feeding a protective device transversely to the direction of delivery of the fasteners and securing devices, and retaining means for a protective device movable in the direction of said delivery.
- 70 19. In a fastener-attaching machine, attaching mechanism, means for delivering fasteners and securing devices therefor to the attaching mechanism, means for feeding a series of protective devices to be operated upon by the attaching mechanism, and a retaining member movable into co-operation with a device of the series succeeding that operated upon.
- 75 20. In a fastener-attaching machine, attaching mechanism, means for delivering fasteners and securing devices therefor to the attaching mechanism, means for delivering to the attaching mechanism a strip of protective devices each of which is formed for co-operation with a securing device, and means for severing the protective devices between the formed portions of the strip.
- 80 21. In a fastener-attaching machine, attaching mechanism, means for delivering fasteners and securing devices therefor to the attaching mechanism, means for deliver-

ing a strip of protective devices to the attaching mechanism, and means for severing the protective devices from the strip, the delivering means being arranged to hold the severed devices.

22. In a fastener-attaching machine, attaching mechanism, means for delivering fasteners and securing devices therefor to the attaching mechanism, means for delivering a strip of protective devices to the attaching mechanism, and means for severing the protective devices from the strip, the delivering means being arranged to hold the strip and severed device during and after the severing operation.

23. In a fastener-attaching machine, attaching mechanism, means for delivering fasteners and securing devices therefor to the attaching mechanism, means for delivering a strip of protective devices to the attaching mechanism, and means for engaging the strip to retain it against displacement in the direction of delivery and thereafter severing a protective device from said strip.

24. In a button-attaching machine, means for delivering buttons and associated staples, staple-setting means co-operating with the delivering means, mechanism co-operating with the delivering and setting means to present thereto washers formed in a strip, and means for severing the washers from the strip.

25. In a button-attaching machine, means for delivering buttons and associated staples, staple-setting means co-operating with the delivering means, mechanism co-operating with the delivering and setting means to present thereto washers formed in a strip, and means for severing the washers from the strip, said severing means being provided with a strip-retaining portion.

26. In a button-attaching machine, means for delivering buttons and associated staples, staple-setting means co-operating with the delivering means, mechanism co-operating

with the delivering and setting means to present thereto washers formed in a strip consisting of successive washers connected by reduced portions, and a cutter acting upon a reduced portion of the strip and having a projection extending between the washers.

27. In a machine for attaching buttons by means of staples, an anvil, a staple driver co-operating therewith, means for delivering washers arranged in a strip between the anvil and driver, and a cutter movable adjacent to the anvil to sever a washer from the strip.

28. In a machine for attaching buttons by means of staples, an anvil, a staple driver co-operating therewith, feeding jaws movable into and out of co-operation with the anvil, and a reciprocatory cutter operating adjacent to the anvil.

29. In a machine for attaching buttons by means of staples, an anvil, a staple driver co-operating therewith, feeding jaws movable into and out of co-operation with the anvil, and a reciprocatory cutter operating adjacent to the anvil, there being washer-engaging projections adjacent to the cutting edge.

30. In a machine for attaching buttons by means of staples, an anvil, a staple driver co-operating therewith, feeding jaws co-operating with the anvil, means for opening and closing the jaws, and a cutter having a portion arranged to hold the strip while the jaws are open and movable to sever said strip when the jaws are closed.

31. In a machine for attaching buttons by means of staples, an anvil, a staple driver co-operating therewith, feeding jaws, a carrier therefor, means for moving the carrier toward and from the anvil, and a cutter having a portion arranged to hold the strip while the jaws are moving from the anvil and to thereafter sever said strip.

In testimony whereof I have signed my name to this specification.

WILLIAM E. ELLIOTT.
